UNITED STATES PATENT OFFICE.

GEORGE BULLOCK AND ARTHUR E. TEMPLEMAN, OF GRAND JUNCTION, COLORADO.

ELECTRIC IRON.

1,282,038.

Specification of Letters Patent. Patented Oct. 22, 1918.

Application filed December 8, 1917. Serial No. 206,146.

To all whom it may concern:

Be it known that we, GEORGE BULLOCK and ARTHUR E. TEMPLEMAN, citizens of the United States, residing at the city of Grand Junction, county of Mesa, and State of Colorado, have invented a new and useful Electric Iron, of which the following is a specification.

This invention relates to electric irons.

10 An object of the invention is to provide a device adapted to be connected with an electric iron for supporting the cord or wires to which the iron is connected in order to support the same out of the way so that the 15 iron may be operated without obstruction thereby.

In the accompanying drawings, in which we have illustrated one form of the invention—

20 Figure 1 is a side elevation of an electric iron having the device in connection therewith.

25 Fig. 2 is an elevation of the device in connection with the iron looking toward one end of the iron.

Fig. 3 is a view illustrating the clasp by which the cord is supported.

30 Fig. 4 is a view showing the construction by which the cord supporting arm is sustained in an upright position.

The electric iron illustrated is of a well known type in which the handle 1 is carried by a support 2 composed of a metallic plate secured to the iron by the connections 3.

35 In the iron illustrated the electric wires, by which the electric current is conducted to the iron for heating the same, are inclosed within a fabricated cord 4, and the iron is provided at its forward end in front of the 40 handle with a socket 5 for receiving the plug 6 in connection with the wires.

45 Our invention consists of a support adapted to be connected with some part of the iron, in this instance with the handle, to support the wires or cord out of the way so that the iron may be operated without inconvenience therefrom. The device may be composed of any suitable or appropriate material provided with means for engaging

the same with the iron, and although we 50 have illustrated the device composed of sheet metal it will be readily understood that it may be otherwise constructed and still remain within the scope of the invention.

55 In the embodiment illustrated the support 55 is composed of sheet metal which is preferably shaped to provide a supporting arm 7 adapted to extend upwardly from the iron as will readily be understood by reference to Figs. 1 and 2. The side edges of the supporting arm 7 are preferably curved and the upper extremity of said arm has two projections arranged to receive and retain the cord or wires between them. As shown the two projections include the converging portions 8 and outwardly diverging portions 9, the latter forming a guide by which the cord is guided when pressed between the projections into the clamping portion thereof. The application of the cord into the clamping 70 device will be readily understood by reference to Figs. 1 and 2 in which it will be seen that the cord is embraced and held between the projections which constitute a species of clamp for holding the cord with sufficient 75 firmness to prevent it from becoming slack and getting in the way of the iron when the iron is in use.

Near the lower end of the arm 7 a hole 10 is formed and a slot 11 of narrower width 80 than the hole 10 extends upwardly therefrom. The hole 10 is of sufficient size to permit the passage therethrough of the head 12 of the screw, pin or other fastening device by which the handle is supported in connection 85 with the support 2. Of course, it will be understood that it is not necessary for the head 12 to be in connection with the fastening device by which the handle is secured to the support; for it is apparent that it is only 90 necessary that the head be rigidly supported by the supporting plate 2 or in connection with the handle.

95 It is preferable that the vertical side walls of the screw, pin or lug supporting the head 12 be flat and of considerable width in the vertical planes in which they are located so that when the cord support 7 is applied

thereto, as shown in Fig. 2, the cord support will be firmly held in an upright position and prevented from turning. By reference to Fig. 2 it will be apparent that in applying the support 2 in connection with the iron the head 12 is passed through the hole 10 and the support 7 is then slipped downwardly on the screw, pin or lug so that the wider portion of said screw, pin or lug engages in the slot 11, as shown, and prevents the supporting arm from turning.

Therefore the mode of connecting the supporting arm with the iron and disconnecting the same therefrom is perfectly apparent as it also the mode of connecting the cord with the clamping device and disconnecting the cord therefrom. It is also apparent that the supporting arm may be connected to and disconnected from the iron wholly independently of the cord and that it is necessary to detach the cord from the iron in order to make connections or disconnections of the supporting arm and vice versa.

From the foregoing it is apparent that we have provided a very convenient and highly useful improvement in electric irons to remove a well recognized inconvenience attendant upon the operations of such appliances. It is apparent that the cord may be connected to the device at any proper place and that the device may be of any desired or necessary length to support the cord out of the way. It is also clear that since the arm 7 extends upwardly outside of the vertical plane of the handle it constitutes no obstruction in the way of the hand or arm of the user, but wholly overcomes the well known inconvenience heretofore encountered in the use of electric irons of the general type herein mentioned.

We do not restrict ourselves to the construction of the device of sheet metal, nor to any particular method of securing the device in connection with the arm, nor to other unessential details or features of construction. What we claim and desire to secure by Letters Patent, is:—

1. In an electric iron, a handle, a supporting arm, a supporting element on one of said parts and the other part being provided with a slot for receiving said element, whereby said arm will be supported above the electric iron in the vertical longitudinal plane of the handle, and resilient arms in connection with the upper end of the supporting arm adapted to embrace between them the electric wire cord.

2. In an electric iron, iron structure, a handle, a supporting arm, a supporting element on one of said parts and the other part being provided with a slot for receiving said element, whereby said arm will be supported in a position extending upwardly from the upper side of the iron in the vertical

longitudinal plane of the handle, and means in connection with the upper end of the supporting arm for releasably engaging the electric wire cord.

3. In an electric iron, a handle support attached to the iron, a handle, an element securing the handle to the support, an arm supported by said element, and means in connection with said arm for supporting an electric wire cord.

4. In an electric iron, a support in connection with the iron, a handle, an element connecting the handle to said support, an arm, means whereby said element will support said arm in an upright position, and means in connection with the upper portion of said arm for engaging and holding an electric wire cord.

5. In an electric iron, a support connected to the iron, a handle, an element holding the handle in connection with the support and extending beyond the outer surface of the support and provided with vertical side walls, an arm having a slot for receiving said element, the side walls of said slot being arranged to contact with the side walls of said element, whereby the arm will be supported in an upright position at one end of the handle, and means in connection with said arm for engaging an electric wire cord.

6. In an electric iron, a support in connection with the iron, an element extending forwardly from said support and having vertical side walls, an arm having a slot arranged to receive said element, the side walls of said slot being arranged to engage the side walls of said element, whereby the arm will be supported in an upright position, and means in connection with said arm for engaging an electric wire cord.

7. In an electric iron, a support in connection with the iron, an element projecting from said support and having vertical side walls, a head on said element, an arm having a hole through which said head may pass and a slot extending upwardly from said hole of narrower width than the width of said head, said slot being arranged to receive said element, and the side walls of said slot being arranged to bear against the side walls of said element whereby the element and said head will support said arm in an upright position, and means in connection with said arm for engaging an electric wire cord.

8. In an electric iron, a handle, a socket in connection with the forward end of the iron in front of the handle arranged to receive the plug of an electric wire cord, a supporting arm in connection with the handle, and means in connection with said supporting arm for engaging and holding the electric wire cord on the forward side of

said arm whereby said arm is maintained between the cord and the hand of the operator engaging the handle.

9. In an electric iron, a handle, a socket in connection with the forward end of the iron in front of the handle arranged to receive the plug of an electric wire cord for heating the iron, a supporting arm, means for removably supporting said arm in an

upright position at the forward end of the handle, and means in connection with said arm above the handle for engaging and holding the electric wire cord, whereby said arm is maintained between the cord and the hand of the operator engaging the handle. 15

GEORGE BULLOCK.
ARTHUR E. TEMPLEMAN.
